DUPLEX DRIVING MECHANISM

Fritz Balzer, Cincinnati, Ohio, assignor to The American Laundry Machinery Company, Cincinnati, Ohio, a corporation of Ohio

Application September 15, 1930, Serial No. 482,124

1 Claim. (Cl. 74—230.13)

My invention relates to duplex driving mechanism and particularly, to a duplex driving mechanism as applied to a fabric treating unit embodying a rotating cylinder for carrying heavy loads of fabric during a treating operation together with apparatus for simultaneously adjusting the driving connections between a plurality of power units and the treating unit whereby each power unit will exert the same pull or driving effort.

Such duplex driving mechanism and simultaneous adjustment of the driving connections is particularly important and greatly to be desired to drive the cylinder of a treating unit when such cylinder contains heavy loads of fabric being treated. In such units, it is customary to rotate the cylinder first in one direction and then in the other after a given number of revolutions of the cylinder in each direction and, when one power unit only is employed having a driving connection with but one end of the cylinder, the cylinder must be made extremely heavy and rigid in order to withstand the torque and twisting stress that is always present but is greatly increased at the time of reversal of rotation of the cylinder.

Heretofore, the cylinders and supporting means have necessarily been made so heavy in order to withstand the stress and strain resulting from the cylinder being driven from one end only that the machines were not usable in certain locations and buildings unless the buildings were specially constructed. The expense of building and cost of the unit was also more or less prohibitive.

In accordance with my invention, a driving connection is provided at each end of the fabric treating cylinder and a separate and distinct power unit is connected to each driving connection, the power units being operated in unison to rotate the cylinder in both directions, and means are provided for so balancing the driving means that the same amount of pull or driving effort is exerted by each power unit.

The objects of this invention are to provide an apparatus of such nature as to prevent consecutive stalling of the motors or power units and thereby stalling of the driven machine; to attain an equal tension on all motor or power unit connections so that each motor or power unit will have an equal pull or exert equal driving effort; and to provide means whereby all motor or power units may be adjusted simultaneously.

Various other objects and advantageous features of my invention may be seen in the following description and one embodiment thereof may be seen in the accompanying drawings wherein

similar characters of reference designate corresponding parts, and wherein:

Fig. 1 is an elevation of a washing machine embodying my invention; Fig. 2 is an enlarged fragmentary view showing particularly a part of the driving connection between the driving and the driven means; Fig. 3 is an enlarged fragmentary plan view showing one of the motor or power unit supports; Fig. 4 is a longitudinal sectional view taken on the line 4—4 of Fig. 3; and Fig. 5 is a 10 sectional view taken on the line 5—5 of Fig. 3.

Referring to the drawings, I have shown one embodiment of my invention in conjunction with a washing machine embodying a tub or container cylinder 1 mounted upon a suitable support 2. 15 The customary rotating cylinder 3 is rotatably mounted within the tub or container 1 and is provided with trunnions 4 extending through suitable bearings in the ends of the tub or container 1. Such rotatable container 3 and trunnion 20 shafts are rotated by way of large gears 5 disposed on opposing ends of the trunnion shafts 4.

A motor or power unit 6 is disposed at each end of the tub or container 1 and these units are provided with small pinions 7 on the ends of their 25 driven shafts 8. As shown, these driven shafts may be in two parts connected together by suitable shaft couplings 9. Such small pinions 7 are operatively connected with larger gears 10 that are mounted on shafts 11 by means of chain belts 30 or other connecting means 12. The shafts 11 have small pinion gears 13 rigidly mounted on their outer ends and arranged to mesh with the large gears 5 which are rigidly mounted on the trunnion shafts 4. Thus, driving connection is made 35 between the motors or power units 6 and the inner rotatable container 3 of the washing machine.

In accordance with my invention, each motor or power unit 6 is mounted on a superstructure above the washing machine just described, these 40 superstructures being identical whereby it is necessary that only one be described. As shown, each motor or power unit 6 is rigidly mounted on a base frame 14 which is slidable on a sub-base frame 15 which is rigidly secured to channel 45 members 16 that connect the end frames of the washing machine together by means of bolts or otherwise, bolts 17 extending downwardly through slots 17' in the base frame 14 providing a means for securing the base frame 14 in adjusted position on the sub-base frame 15.

The upper surface of the sub-base frame 15 is provided with two parallel rectangular grooves 18 that coincide with two rectangular companion grooves 19 on the under surface of the base 55

frame 14. Rectangular shaped bars 20 are fitted into the coinciding grooves 18 and 19 and prevent longitudinal movement of the base and sub-base frames relative to each other but permit relative lateral movement or adjustment. Thus, it will be understood that the chain belt 12 may be tightened or loosened by adjusting the base frame 14 with the power unit in one direction or the other relative to the sub-base frame 15 since the small gear 7 is located to the rear although above the large gear 5, see Fig. 2.

To provide for such movement or adjustment of the motor or power unit base frame 14 and the motor or power unit 6 secured thereon a threaded shaft 21 that is held against longitudinal movement by means of collars 22 and 23 as shown in Fig. 5 is rotatably mounted on the motor or power unit sub-base frame 15 and has its threaded portion disposed in a threaded portion 24 of the base frame 14 that is held on the base frame by a pin 24' whereby rotation of the shaft 21 will cause movement of the base frame 14 relative to the sub-base frame 15 in one direction or the other depending upon the direction of rotation of the shaft. It will be noted that the shaft 21 extends from front to back of the machine parallel to the two bars 20 and preferably equidistant from such bars.

Rigidly secured on the shaft 21 is a worm gear 25 that is in meshing relation with a worm 26 rigidly mounted on a rotatable shaft 27 which extends from one end of the machine to the other, the shaft and worm gear being held against longitudinal movement by brackets 28 that form bearings in which the shaft 27 rotates. A worm 26 is provided for each motor or power unit employed, the worms being mounted on the same shaft 27 so that adjustment of the motor or power units will be simultaneous regardless of their movement.

In the operation of this part of the apparatus, when it is desired to adjust the motor or power units, the bolts 17 are loosened and the shaft 27

rotated in any well known manner to move the motor base frame 14 in one direction or the other relative to the sub-base frame 15 through the medium of the worm 26, worm gear 25, and threaded screw shaft 21 hereinbefore described, such movement of the motor or power unit and its base frame tightening or loosening the chain belts 12 as will be readily apparent. Any desired means or method of adjusting the driving connections individually may be provided or used as will be apparent.

Referring to the drawings and the preceding description, I have provided a means for simultaneously adjusting the belt driving connections between a plurality of motor or power units and a single driven element whereby the same amount of pull or driving effort will be exerted by each motor or power unit. This is highly advantageous in that it will prevent stalling of the driven element by reason of consecutive stalling of the motor or power units and will, in a large measure, eliminate the strain and torque usually found in a shaft that is driven from one of its ends only and supports a heavy or large driven element or in the main body portion of a driven element which, as in this instance, is a cylinder supported at each of its ends by means of trunnions and bearings.

What I claim is:

In apparatus of the character described, and including a pair of motors and means to be driven thereby, each motor having driving connection with said driven means and including a belt, a base frame for each motor, each motor being secured on its base frame, a sub-base frame for each base frame, each base frame being mounted on its sub-base frame for adjustment thereon in a direction to adjust the corresponding belt, and means interconnecting said base frames for their coincident adjustment to provide simultaneous adjustment of both said belts.

FRITZ BALZER.
